SWITCHING MECHANISM FOR MULTIPLE WAY ADAPTERS

George Raft, Sydney, New South Wales,
AustraliaApplication January 14, 1941, Serial No. 374,390
In Australia January 26, 1940

3 Claims. (Cl. 200—51.03)

The present invention relates to means whereby a circuit may be provided from a source of current such as a lamp socket to two or more socket fittings in a selective manner for instance by the operation of a pull cord attached to a multiple way adapter.

The invention will be described in relation to a multiple way adapter but it will be understood that it can be equally applied to switches per se.

The invention is preferably housed in a casing of insulating material divided centrally into two parts or the said casing may be hollow or cup shaped and adapted to be closed by a cover.

The casing is provided with a plurality of limbs, three for example, one of which is in the form of a plug and is adapted for connection with the bayonet joint of a lamp fitting from which current is to be taken. This plug has two contacts embedded therein.

The other two limbs of the casing are bayonet or like socket fittings and each contains two spring plunger type contacts. Each of the four spring contacts connects inside the casing with a respective spring strip contact. One of the said spring strip contacts of each of the said bayonet socket limbs is disposed in a common plane while the remaining spring contact strips are disposed in another common plane either above or below the former plane assuming the casing to be laid flat.

Centrally within the casing there is a metallic spindle which is electrically connected to one of the contacts of the plug limb of the casing. The other contact of the said limb is connected to a flat contact member having an annular portion disposed concentrically with respect to the spindle and insulated therefrom.

A rotor is mounted upon the spindle and consists of an insulated disc, on either side of which is formed an insulated ratchet portion; the whole of which however may be mounted in one piece.

Upon each ratchet face a metallic section is placed having portion thereof bent at right angles over some of the ratchet teeth on the insulated ratchets.

In the case of a two way adapter at least two metallic teeth are thus provided on each ratchet portion for each limb of the adapter, so as to give effective intermittent action.

The contact springs of the adapter socket pins in the respective planes engage the respective ratchets on either side of the centre of the insulated rotor depending upon in which of the two planes they are disposed.

One of the said metallic sections has a slotted portion equivalent to a face ratchet which is adapted to be engaged by detents formed on an operating segment having a pull cord and being mounted to oscillate upon the said spindle.

In order that the invention may be more readily understood reference will now be made to the accompanying drawing wherein:

Figure 1 is an inside view of one half of the 10 casing with the rotor removed showing the three bottom contacts and one of the metal sleeves.

Figure 2 is a view similar to Figure 1, with the rotor in position on the central spindle and the three top contacts in position with the top 15 cover or half of the casing removed.

Figure 3 is a plan view of the four toothed 20 rotor with the brass insert in position.

Figure 3a is a side elevation of the rotor seen in Figure 3 looking from the left.

Figure 4 is an inverted plan view of Figure 3.

Figure 5 is a side elevation of the top contact from the main branch, showing the ratchet spring and fixing collar on the central spindle.

Figure 6 is a plan view of the form of ratchet 25 used with the four tooth rotor.

Figure 7 is a plan view of a modified form of rotor having eight teeth with the brass insert removed.

Figure 8 is a side elevation of the rotor seen 30 in Figure 7 looking from the right, while

Figure 9 is a section on the line 9—9 of Figure 7.

Figure 10 is a plan view of the top brass rotor contact for use with the rotor seen in Figure 7, 35 while

Figure 11 is an inverted plan view of the lower brass rotor contact therefor.

Figure 12 is a plan view of that form of ratchet member used with the eight toothed rotor, and

Figure 13 is a side elevation thereof.

As illustrated, the casing 20 has three limbs 21, 22 and 23 and is divided into two parts longitudinally. The limb 21 is provided with bayonet pins 24 for connection to a lamp socket or the like from which current may be received for supplying one or both of the other limbs 22 and 23 each of which is fitted with a sleeve 25 in well known manner.

The limb 21 has contacts 26 and 27 and the 50 limbs 22 and 23 have spring plunger type contacts 28, 29, 30 and 31 respectively. Spring strip contacts 32, 33, 34 and 35 are connected respectively to the contacts 28, 29, 30 and 31. It will be noted from Figure 2 that the spring strip contacts 32 and 35 are in the same plane and

that the spring strip contacts 33 and 34 are both in another plane.

A metallic spindle 36 is secured at one end in one part of the casing 20, see Figure 1, and at its free end is in electrical engagement with the contact 27 of limb 21 by a flat fitting 37, see Figures 2 and 5. The other contact 26 of limb 21 is connected to a flat contact member 38 having an annular portion 39 which gives clearance to insulate it from the spindle 36.

In order to bring about the desired selection or switching action for the contacts of limbs 22 and 23 a rotor 40 Figures 2, 3, 3a, and 4 or alternatively Figures 7, 8 and 9 is provided. The rotor may be provided with four teeth as seen in Figures 3 and 3a or with eight teeth as seen in Figure 7 or any multiple thereof.

The rotor 40 which is mounted to rotate upon the spindle 36 is formed with a ratchet portion 41 and 42 disposed on either side of a central portion 43, all formed of insulating material.

A metallic section 44 is secured on the face of ratchet portion 41 and a metallic section 45 is secured on the face of ratchet portion 42. The sections 44 and 45 are stampings or pressings and form, or extend over, some of the teeth of the said rotor 40.

In the case of a two-way adapter switch as illustrated, at least two metallic teeth 46 are provided by the metallic sections 44 and 45 for each current distributing limb so as to give effective intermittent action.

The space occupied by the insulated teeth which are disposed between the first and last of the metallic teeth may be formed as a curved surface instead of being provided with teeth.

Referring to Figures 1 and 2 it will be seen that the spring strip contacts 32 and 35 are adapted to engage the metallic teeth 46 of ratchet portion 41 while the spring strip contacts 33 and 34 are adapted to engage the metallic teeth 46 of ratchet portion 42.

The metallic section 44, Figures 3 and 10, has face ratchet teeth 47 which are adapted to be engaged by detents 48 formed on an operating segment 49, see Figures 2 and 6 or 12 and 13 to which the usual pull cord 50, see Figure 2, is attached the said cord 50 passing through hole 51 in the casing 20. The operating segment 49 is loosely mounted upon the metallic spindle 36 and is adapted to be oscillated by the said pull cord 50 against the action of a spring 52, see Figure 5. The spring 52 is concentrically mounted upon the metallic spindle 36 and is secured at one end to a tongue 53 on the operating segment 49 and at its other end to the claws 54 on the flat fitting 37, see Figures 2 and 5.

To limit the forward and return travel of the operating segment 49 stops 55 are formed integral with the flat fitting 37, see Figures 2 and 5, and are engaged by the upturned portion 56 of the said operating segment 49, see Figures 6 and 12.

In use, when the cord 50 is pulled the respective spring strip contacts 32 and 35, and 33 and 34 engage the metal sections 44 and 45 respectively and alternately the insulated portions 41 and 42 respectively thereby supplying current to the two limbs 22 and 23.

As illustrated in Figure 2 the strip contacts 32 and 33 are on metal contacts 44 and 45 and strip contacts 34, 35 are on insulated portions 41 and 42 respectively of the rotor 40.

In this position a two pole connection is made from limb 21 to limb 22 via parts 27, 31, 36, 44, 32, 28, 29, 33, 45, 38 and 26.

If now the cord 50 is pulled to move the rotor 40 clockwise the strip contacts 32 and 33 leave the parts 44 and 45 respectively and engage the insulated parts 41 and 42 the circuit to limb 22 will be broken at 44 and 45 and neither limb 22 nor 23 will receive current.

Similarly the limb 23 may be connected and disconnected electrically with the limb 21 through spring strip contacts 34 and 35 and their associated parts.

As illustrated in Figure 2 only, limb 22 is in electrical connection with limb 21, but as there are two or a multiple of two metal teeth 46 on the rotor 40 selectivity may be arranged with regard to the supply of current to one or both or neither of the limbs 22 and 23 in accordance with known intermittent switch action practice.

I claim:

1. A multiple way switch mechanism for making and breaking both sides of a circuit from a source of current to a plurality of pairs of distributing terminals comprising, a casing of insulating material, a spindle mounted on the casing, a rotor mounted for rotation on the spindle, an insulated portion and a metal portion disposed in one plane of said rotor, a second metal portion and a second insulated portion disposed in another plane on said rotor, a disc of insulating material extending circumferentially of the rotor between the first and second metal portions, means providing an electrical connection from one side of an electrical source to said spindle, means providing an electrical connection between the spindle and one of said metal portions, a contact member surrounding said spindle in a spaced relation engaging the other metal portion on said rotor and connected to the other side of said source, a plurality of circumferentially spaced contact strips arranged in a common plane for engaging one metal portion, and a plurality of circumferentially spaced contact strips arranged for engaging the other metal portion of the rotor and separated from the first contact strips adjacent the rotor by means of said disc.

2. A multiple way intermittent switching mechanism for connecting a source of current having two supply terminals in selective manner with at least two distributing points each having two distributing terminals, comprising a casing of insulating material, a spindle secured at one end to the casing and being electrically connected to one of the supply terminals, insulated portions and metallic sections comprising a rotor mounted for intermittent rotation upon the spindle, said metallic sections on the rotor being of toothed formation and separated longitudinally by an insulated portion, one of said metallic sections on the rotor being electrically connected to the spindle and thence to the supply terminal and the other of said metallic portions of the rotor being electrically connected to the other of said supply terminals, a spring contact for a distributing terminal of one distributing point, a spring contact for a distributing terminal of a second distributing point both of said spring contacts engaging one and the same metallic portion of the rotor, spring contacts for the remaining distributing terminals of the respective distributing points engaging the other of the metallic portions, and means mounted upon the spindle for intermittently rotating the rotor.

3. A multiple way intermittent switching mechanism for connecting a source of current having two supply terminals in selective manner with at least two distributing points each hav-

ing two distributing terminals, comprising a casing of insulating material, a spindle secured at one end to the casing and being electrically connected to one of the supply terminals, insulated portions and metallic sections comprising a rotor mounted for intermittent rotation upon the spindle, said metallic sections on the rotor being of toothed formation and separated longitudinally by an insulated portion, one of said metallic sections on the rotor being electrically connected to the spindle and thence to the supply terminal and the other of said metallic portions of the rotor being electrically connected to the other of said supply terminals, a spring contact for a distributing terminal of one distributing point, a 15 spring contact for a distributing terminal of a second distributing point both of said spring con-

5 tacts engaging one and the same metallic portion of the rotor, spring contacts for the remaining distributing terminals of the respective distributing points engaging the other of the metallic portions, face ratchet teeth formed upon a metallic section connected electrically to the spindle, a segment loose on the spindle and having detents for engaging the teeth of the metallic section, a coiled spring disposed concentrically upon the spindle and secured at 10 one end to the segment and at the other end to a flat contact fitting, and stops formed integral with the contact fitting to engage the segment and ensure alignment of the rotor with the contact springs.
